UNITED STATES PATENT OFFICE.

HAROLD CARLE, OF BUFFALO, NEW YORK, ASSIGNOR TO F. N. BURT COMPANY, LIMITED, OF TORONTO, ONTARIO, CANADA, A CORPORATION OF THE PROVINCE OF ONTARIO, DOMINION OF CANADA.

DRUM MACHINE.

Application filed June 29, 1921. Serial No. 481,233.

To all whom it may concern:

Be it known that I, HAROLD CARLE, a subject of the King of Great Britain, residing at Buffalo, in the county of Erie and State 5 of New York, have invented certain new and useful Improvements in Drum Machines, of which the following is a full, clear, and exact description, such as will enable others skilled in the art to which it appertains to 10 make and use the same.

This invention relates to machines for making boxes and the like and with respect to its more specific features to machines for automatically making box parts from supplies of paper strip especially when the 15 strips are in web form.

One of the objects of the invention is the provision of a machine for rapidly and continuously automatically making box 20 parts, which may be termed "drums," they having a head and a flange.

Another object of the invention is the provision of efficient mechanisms cooperating to fabricate and assemble heads with the 25 flanges of drums, especially where the heads are made of soft frangible paper stock.

Another object of the invention is the provision of practical mechanism for feeding relatively soft head strip material, cutting heads therefrom and supplying the 30 severed heads to the mechanism for assembling the same with the flanges.

Another object of the invention is the provision of simple and efficient folding 35 mechanism adapted especially for folding the circular margins of head strips or blanks into relatively smooth cylindrical shape.

Another object of the invention is the provision of a simple and practical device 40 for discharging articles from formers on which they have been made.

Other objects will be in part obvious and in part pointed out hereinafter.

The invention accordingly consists in the 45 features of construction, combinations of elements and arrangement of parts which will be exemplified in the construction hereinafter set forth, and the scope of the application of which will be indicated in the 50 following claims.

In the accompanying drawing forming part of this specification wherein similar reference characters refer to similar parts throughout the several views,

Figure 1 is a plan view of a machine embodying the invention; 55

Fig. 2 is a front elevation of the machine;

Fig. 3 is a side elevation looking at the right of Fig. 1;

Fig. 4 is a rear elevation of the machine; 60

Fig. 5 is a side elevation looking at the left of Fig. 1;

Fig. 6 is a horizontal section through the machine taken somewhat above the main driving shaft and showing the arrangement 65 of several of the driving elements;

Fig. 7 is a detail of the operative connection for rotating the turret head which carries the formers;

Fig. 8 is a vertical section through the 70 turret head and its shaft, showing one of the formers and its driving and discharging device;

Fig. 9 is a plan of the turret head, showing 75 one of the formers, parts being broken away for clearer disclosure;

Fig. 10 is an end view of one of the formers;

Fig. 11 is a view similar to Fig. 10 with 80 the vacuum plate removed;

Fig. 12 is a view similar to Fig. 11 with the keeper plate removed;

Fig. 13 is an elevation, partly sectional, of the mechanism for feeding the head strip, severing blanks therefrom and supplying the 85 blanks to the formers;

Fig. 14 is a detail illustrating the devices for operating the feed rolls for the head strip;

Figs. 15 and 16 are respectively a side 90 elevation and a horizontal section of a valve device for controlling the vacuum grip associated with the cutting die illustrated in Fig. 13;

Fig. 17 is a rear detail view of the 95 bracket for supporting the cutting die and the vacuum pipe leading therefrom;

Fig. 18 is a vertical central section through Fig. 17;

Fig. 19 is a side elevation of the devices 100 for feeding, applying and severing the flange strip material to the formers at one of the stations;

Fig. 20 is a view of the devices of Fig. 19, looking at the opposite side; 105

Fig. 21 illustrates a detail of the presser roller of Fig. 20;

Fig. 22 is a side elevation of the devices

- operating at one of the stations to fold the margins of the head strips, or blanks, on the formers, and to press the coiled flange strip;
- 5 Fig. 23 is a vertical central section through the folder of Fig. 22, and the former with coiled flange strip cooperating therewith;
- Fig. 24 is a detail of the presser illustrated in Fig. 22;
- 10 Fig. 25 is a side elevation of the devices for feeding, pressing and severing another flange strip;
- Figs. 26, 27, 28, and 29 are detail views of various devices appearing in Fig. 25;
- 15 Fig. 30 is a side elevation of the device for discharging the paper articles from the formers; also of the safety device cooperating therewith;
- Fig. 31 is an end elevation of the construction shown in Fig. 30;
- 20 Fig. 32 is a detail of the safety device illustrated in Fig. 30;
- Fig. 33 illustrates the clutch shifting device with which the safety device of Fig. 25 30 cooperates;
- Fig. 34 illustrates the former with the head strip or blank applied thereto in position to be folded;
- Fig. 35 is similar to Fig. 34 but illustrates 30 the first coiled flange strip on the former;
- Fig. 36 is similar to Fig. 35 but shows the head strip folded onto the coiled flange strip;
- Fig. 37 is similar to Fig. 36 but shows 35 the second coiled flange strip overlying the folded margin of the head strip and the first coiled flange strip;
- Fig. 38 illustrates a portion of the first coiled flange strip and the glue lines 40 thereon;
- Fig. 39 illustrates a portion of the second coiled flange strip, glued over all;
- Fig. 40 is a detail of a connection for operating the cutting die;
- 45 Fig. 41 is a perspective view of a "drum;" and
- Fig. 42 is a perspective view, partly sectional, of a box equipped with a "drum."
- The disclosure of the invention will be 50 facilitated by first setting forth certain of the primary operations performed. Reference being made to Figs. 34 to 37 inclusive, there is shown a head strip or blank 1 of paper lying across the end of a cylindrical former, or mandrel. The application of the head strip 1 is affected at the first station. At the second station another strip, or blank, is coiled around the cylindrical former into a plurality of plies 2.
- 55 At a third station the projecting margin 3 of the head strip is folded down onto the coiled flange strip and adheres thereto as illustrated in Fig. 36. At a fourth station another flange strip 4 is coiled around the 60 first coiled strip and overlies the folded margin of the strip 1. The article produced, as just described, may then be discharged from the former by pushing it to the left, considering Fig. 37.
- Referring now more specifically to the 70 drawings, the frame of the machine comprises a main table 5 which supports an auxiliary table 6 thereabove. On the main table is an electric motor 7. The numeral 8 indicates a rotary vacuum pump driven from the motor by the gears 9 and 10. The numeral 11 indicates a vacuum tank slung beneath the table 5 and communicating with the pump by way of the pipe 12. By operating the pump, the pressure in the 75 tank 11 is reduced, and the two provide an exhaust device for energizing certain vacuum grip posts hereinafter mentioned. The numeral 13 indicates the main driving shaft of the machine supported in bearings 80 upstanding from the table 5 and driven from the motor through the instrumentality of the gears 14, 15 and 16. The numeral 17 indicates a hand wheel for turning the main driving shaft 13 at will. 85 The numeral 18 indicates a clutch which cooperates directly to transmit the rotation of the gear 16 to the main driving shaft 13. A suitable clutch shifter 19 is employed to actuate the clutch. The numeral 20 (Fig. 6) indicates a main 90 cam shaft also supported in bearings upstanding from the table 5 and driven from the shaft 13 by sprocket and chain connections indicated at 21.
- The numeral 22 indicates a vertical rotatable turret head shaft supported in suitable bearings carried by tables 5 and 6 the lower end of this shaft carrying a mutilated pinion 23 which cooperates with a mutilated gear 24, the rotation of the latter effecting intermittent rotation of the turret head shaft 22 and locking this shaft between its intervals of motion. The gears 23 and 24 rotate in horizontal planes, and the gear 24 is at the lower end of a short 100 vertical shaft 25 supported in bearings carried by the table 5 and having a bevel pinion 26 meshing with a bevel pinion 27 on the main driving shaft 13. As the main driving shaft rotates, intermittent rotation 105 of the turret head shaft is effected. Sleeved on the turret head shaft 22 is a large bevel gear 27 (Fig. 8) carrying a spur gear 28 in mesh with another spur gear 29 carried by a vertical shaft 30 supported in bearings 110 on the tables 5 and 6, the lower end of the shaft 30 having a bevel gear 31 (Fig. 3) meshing with a similar bevel gear 32 on a short horizontal shaft 33, the latter having a mutilated gear 34 driven by a mutilated 115 gear 35 on the end of the main driving shaft 13. Thus as the main driving shaft rotates, rotation of the bevel gear 27 at intervals is effected, the bevel gear 27 rotating on the turret head shaft 22. 120
- 125 130

At the upper end of the turret head shaft 22 is a turret head 36 keyed to the shaft 22 so as to rotate therewith. The turret head 36 has a plurality of horizontal radially extending bearing arms 37 rotatable therewith. 5 Rotatably mounted on the outer end of each arm is a cylindrical former or mandrel 38 (Fig. 8). There being six bearing arms in the present embodiment, there will be six 10 (6) formers or mandrels. Inasmuch as the construction of and operations connected with each former and its bearing arm are the same, a description of one will suffice for all. The numeral 39 indicates a sleeve rotatable on the arm 37 and having a bevel pinion 40 in mesh with the bevel gear 27. The former 38 is illustrated as an integral part of the sleeve 39. The side of the former 38 has a vacuum port 41 for gripping one of the 15 flange strips, and the front end of the former has one or more vacuum ports 42 for gripping the head strips. The bearing arm 37 has a circumferential or annular groove 43, and the former 38 has a vacuum conduit 44 leading from the side port 41 to this annular groove. In the arm 37 is a vacuum conduit 45 (Fig. 9) in communication with the annular groove 43 and also opening into the upper 20 face of the turret head 36 as indicated at 46 (Fig. 8). For the purpose of having a large vacuum gripping area at the side of the former 38, the cylindrical side surface may be flattened and recessed, or dished slightly, as by the provision of the channels 47, which 25 communicate with the port 41 so that the gripping effect will take place throughout the extent of the channels 47. Also in the arm 37 is a second vacuum conduit 48 by means of which the vacuum ports 42 in the 30 end of the former are energized and de-energized. In the present embodiment the vacuum ports 42 are openings in a removable vacuum plate 49 fastened in a recess in the front end of the former 38. 35 On the inner face of the vacuum plate 49 is a circular groove 50, (Fig. 10) providing with the bottom wall of the recess in the former, an annular vacuum conduit, having branches 51 respectively in 40 communication with the openings or vacuum ports 42 in the plate. The vacuum conduit 48 leads to a port 52 in the end of the arm 37. The numeral 53 (Figs. 8 and 11) indicates a flat keeper plate set over the 45 end of the arm 37 and having a pin 54 to prevent rotation on the arm, the keeper plate being fastened by a screw 55. In this keeper plate is an opening or port 56 in registry with the port 52 at the end of the vacuum 50 conduit 48. The port 56 registers with the annular groove 50 on the inner face of the vacuum plate 49. In this way the former 38 is retained on the arm 37 by the keeper plate 53, and the vacuum ports 52 in the 55 end of the former are at all times in com- munication with the vacuum conduit 48, and the structure provides for the ready removal of the formers from the bearing arms 37 and also for the removal or renewal of the vacuum plate 49. 60 Like the vacuum conduit 45, the vacuum conduit 48 opens into the upper face of the turret head 36 as indicated at 57 (Fig. 9) the vacuum conduits 45 and 48 being independent of each other. The vacuum plate 49 being set into a recess in the end of the former 38 may be fastened in place by screws 58, and rubber cushions 59 may be interposed between the inner face of the vacuum plate and the former to assist in steadyng and rectifying the vacuum 65 plate.

Overlying the upper face of the turret head 36 is an automatically operable valve or valve plate 60 having a circular chamber or groove 61 with which the vacuum ports 46 and 57 of the vacuum conduits 45 and 48 are adapted to register at certain portions of their rotary path. Communication between the exhaust device and the vacuum conduits 45 and 48 is established and cut off by this 70 single valve. Communicating with the chamber 61 is a flexible vacuum pipe 62 which, through suitable piping as 63, communicates with the vacuum tank 11. When the vacuum conduits in the arms are in communication with the chamber 61 in the vacuum plate 60 they are also in communication with the vacuum tank 11 through the pipe 62 and 63 so that the vacuum ports at the sides and the ends of the formers are energized. 75 When the vacuum ports 46 and 47 in the turret head pass out of communication with the chamber 61 they register respectively with atmospheric openings 64 and 65 (Fig. 9) in the plate 60 so that the vacuum effect 80 at the side and at the end of the former is relieved. In order to energize and deenergize the vacuum conduits in the arms at certain times the valve 60 is oscillated, and this may be effected by means of a connect- 85 ing rod 66 (Figs. 1 and 2) pivoted to the valve 60 and to a bellcrank lever 67 operated by a connecting rod 68 from a cam 69 on the main cam shaft 20, the cam being shaped to effect the movement of the valve at the 90 predetermined time desired. The valve plate 60 is pressed against the turret head by a spring 69.

The operations of the turret head and the formers will now be clear. The continuous rotation of the main driving shaft 13 will cause intermittent rotation of the turret head 36 with consequent intermittent translation of the bearing arms 37 and the formers 38 in an endless path. At the stations of rest in the endless path the head strips and the flange strips hereinbefore referred to are applied to the formers as will be more fully explained in detail hereinafter, rotation of the formers at their stations of rest participating 95

in the application of some of said strips. Rotation of the formers at their stations of rest occurs simultaneously and is effected by the bevel gear 27 which is rotated at that time 5 through the train of gears 28 and 29. Thereupon translation of the formers is resumed by rotation of the turret head, the bevel gears 40 rolling on the then stationary gear 27 to their next positions of rest.

10 Referring now to Fig. 1 of the drawings the several formers 38 are indicated at the six (6) stations of rest lettered respectively, A, B, C, D, E, F. At station A the head strip, or blank, is applied across the front 15 end of the former as illustrated diagrammatically in Fig. 34. This strip may be provided in any suitable manner but in the present embodiment is taken from a strip or web of soft, readily frangible paper. This 20 paper web is indicated by the numeral 70 and comes from supply roll 71 rotatably supported on bracket 72. The web 70 passes between a pair of web advancing feed rollers 73 which intermittently move the web to position 25 to have head strips severed therefrom and supplied to the formers at station A. The feed rollers 73 have suitable rubber covered surfaces for frictionally feeding the web and are pressed toward each other by the spring 74, the tension of which is adjustable. Intermittent operation of the rollers is effected by intermeshing gears 75 and 76 thereon driven by a larger gear 77 on a shaft 78, the gear 77 having a ratchet wheel 79 30 with which cooperates a pawl 80 operated from the cam 81 through the instrumentality of the rock lever 82 and connecting rods 83 and 84 (Fig. 14), a spring 85 being employed to urge the cam follower 86 against 35 the cam 81.

The numeral 87 indicates a reciprocal head strip feeder which, in the present embodiment, is a circular male cutting die adapted to sever the strips from within the margins 40 of the web 70 and to apply the severed strips to the formers at station A. The die 87 is a cylindrical hardened steel block which cooperates with a female cutting die 88 to sever the head strips. In the advance end of 45 the die 87 are vacuum ports 89 at the ends of vacuum conduits 90, these conduits communicating with a vacuum pipe 91 movable with the die and having a flexible extension 92 communicating with a pipe section 93 50 which latter extends to a rock plate 94 in registry with a port 95 in said plate. Lying closely against the rock plate is a stationary cut-off plate 96 having a port 97 with which the port 95 is adapted to move into and out 55 of registry. The stationary cut-off plate 96 is pivoted on the bracket 98 and has a bearing projection 99 on which the rock plate 94 is sleeved, a spring 100 being interposed between the rock plate and a collar 101 on the 60 bearing 99 to keep the two plates in close con-

tact. Oscillation or rocking of the plate 94 may be effected through a connecting rod 102 one end of which is pivoted to the plate, the other end being connected to a cam follower 103 which cooperates with a cam 104 70 on the main cam shaft 20, a spring 103' assisting in the cooperative result. By movement of the plate 94, energization and de-energization of the vacuum ports in the die 87 is effected independently of that of the 75 ports in the formers, or mandrels 38. The port 97 is in communication with the vacuum tank by way of the pipe 104'.

Between the feed rollers 73 and the supply roll 71 the web is acted on by a spring tension device consisting of a frame 105 pivoted intermediate its ends at 106 to a stationary bracket 107. One end of a spring 108 is attached to the frame 105 and the other end to the bracket so that the spring acts to rotate 85 the frame 105 in one direction, the extent of its movement being determined by a stop pin 109 which cooperates with the side of the bracket 107. The head strip web 70 coming from the supply roll 71 passes over the anti-friction rollers 110 and 111 carried by the frame 105 and thence over a guide roll 112 to the feed rolls 73. When the feed rolls 73 are operated to advance the web 70 past the cutting die 87, the tension frame 105 rotates 95 under the pull of the feed rolls so as to supply the necessary length of web to these rolls. After the feeding movement of the rolls has been effected tension on the web may be preserved by movement of the frame 105 in the 100 opposite direction, which latter movement may unroll a further amount of web from the supply roll 71.

In the present embodiment the advance movement of the cutting die severs a head 105 strip from the web and carries the severed strip and applies it across the front end of the former 38 at station A. The cutting die 87 moves in a cylindrical housing 113 carried by bracket 114 upstanding from the 110 table 6. This bracket serves as a support for a reciprocal rod 115 to which the cutting die 87 is removably fastened by the screws 116'. To the rear end of the rod 115 is pivoted one end of a link 116 the opposite end being pivoted to one of a pair of toggle links 117, in turn connected to a link 118. The link 118 is pivoted to an arm 119 of a rock shaft 120, the latter having another arm 121 connected by a link 122 115 to a bellcrank 123 which in turn, through link 124, is actuated by a cam 125 on the main driving shaft 13, a spring 126 being employed to keep the cam follower in cooperation with the cam 125. A guide rod 127 120 is pivoted to the bracket 114 at 128, the rear end of the rod 127 being slotted at 129 for the reception of a pin 130 carried by the link 116, the pin 130 engaging both tines of a fork 131 overlapping opposite 130

sides of the rod 127. A vertical recess 132 in the rod 127 receives the link 116. The numeral 133 indicates a bracket on which is fulcrumed a lever 134 the upper end of this lever being pivoted at 135 to the fork 131, the lower end of this lever being adjustably connected to a link 136 in turn connected to an arm 137 of a rock sleeve 138 on the shaft 120. Also carried by the 10 rock sleeve 138 is another arm 139 linked to bellcrank lever 140 which, through connecting rod 141, cooperates with the cam 142 on the main driving shaft 13, a spring 143 being employed to maintain cooperative relation between the cam follower and the cam 142.

The web 70 having been advanced into position in front of the cutting die 87, the link 118 will be moved upwardly by the 20 cam 125 and rock the link 16 on the guide rod 127 thus advancing the die 87 until a head strip is severed from the web. The link 116, which thus acts as a lever, will fulcrum on the pin 130 held from movement at this time. Thereupon, by operation of the cam 142 the lever 134 will be actuated in the proper direction to further advance the die 87 and the severed strip to the former 38. Upon the severance of 30 the strip 138 the vacuum ports 89 in the die 87 will be energized to grip the severed strip and hold it until it is applied across the front end of the former 38. Thereupon the vacuum grip of the die upon the strip 35 will be relieved by movement of the rock plate 94 of the vacuum control device, and the end ports of the former 38 will be energized by movement of the valve plate 60 and cause the severed strip to be held on 40 the former 38. The timing of the energizing and deenergizing of the vacuum ports in the die and former respectively will be such as to deenergize the ports in the die prior to the retractive movement of the die 45 and prior to rotary movement of the former from station A. It will be observed that the control of the vacuum ports in the die is separate from that of the ports in the former 38.

50 The former with the head strip gripped to its front end will then be translated to station B. At this station a flange web, or flange strip, of fairly heavy paper is coiled around the former 38 so as to abut 55 the head strip 1. The coiling is affected by rotation of the bevel gear 27 which rotates the former a plurality of times at station B, in the present instance three times, so as to provide a three ply coil. In 60 the present embodiment the devices for applying the flange strip at station B are as follows:—(Figs. 1, 2, 4, 19, 20 and 21) At 150 is indicated the supply roll for the flange strip. The strip 151 coming from 65 this roll passes over a guide roll 152 on a glue tank 153, thence over a glue roller 154 dipping into the glue in the tank, thence over another guide roller 155 and thence over a flange strip feeding wheel 156 the operation of which wheel advances the flange 70 strip from the supply roll 150 and provides a loop or slack of such strip as illustrated at 157. The feed wheel 156 and the devices for energizing the vacuum ports therein may be similar to the pneumatic strip feeding wheel disclosed in applicant's co-pending application No. 435,827 filed January 8, 1921, and reference is made to said application for full disclosure thereof.

It is sufficient to state herein that the feed 80 wheel 156 is rotated continuously by means of a belt 158 cooperating with a pulley 159 on the shaft of feed wheel 156 and a pulley 160, which latter is rotated by a sprocket chain 161 driven from the main cam shaft 85 13. As will be understood from the companion application referred to the feed of the flange strip 151 is effected when the vacuum ports in the feed wheel 156 are energized to grip the strip, the wheel 156 rotating idly under the strip when the vacuum ports therein are not energized. The flange strip 151 coming from the feed wheel 156 enters between the jaws 162 and 163 of a reciprocatory gripper sliding on a bracket 164 95 95 and so located as to advance the end of the gripped strip to position over the vacuum port 41 in the former 38. Reciprocal movement of the gripper is effected by a cam 165 on an auxiliary cam shaft 166, this cam co-operating with the cam roll 167 on a slide rod 168 pivotally connected to a rock lever 169 in turn connected to the lower gripper jaw 163 by a rod 170, the feeding movement of the gripper being effected by a spring 100 171, and the retractive movement being positively effected by the cam 165. The numeral 172 indicates a knife to sever the web 151 into flange strips, the movements of the knife 172 being effected by another cam 173 110 on the shaft 166. At 174 is indicated a presser roller which cooperates to press the flange strip toward the former as the former rotates, so as to effect a compact coil on the former. The presser roll 174 is moved toward 115 the former 38 by a spring 175 and away therefrom by another cam 176 on the shaft 166. It may be stated that the details of the devices for operating the knife 172 and the presser roll 174 may be the same as set forth 120 in the companion application above referred to. In the present instance, however, the presser roll 174 has a portion 177 which is out of contact with the flange strip during the pressing operation, and has circular 125 flanges 178 which contact with the strip to effect the pressing.

The glue roller 154 coats the flange strip 151 lengthwise with separate lines of glue, one line on each margin and one line inter- 130

mediate its margins as indicated at 180, 181 and 182 (Fig. 38) portions of the width of the web being uncoated by the roller 154.

As the gripper jaws 162 and 163 advance, 5 the end of the flange web 151 is applied to the former 38 at station B, over the vacuum port 41 and the vacuum channels 47 hereinbefore referred to. Thereupon movement of the valve plate 60 energizes the port 41 and 10 effects gripping of the web to the side of the former. The former then rotates a plurality of times at station B and coils a portion of the web thereon, the roller 174 contacting with the strip 151 at its uncoated portions 15 during the coiling, the portion 177 of the roller extending across the intermediate line of glue 182 out of contact with the glue so that coating of the roller with glue is avoided. It may be noted here that the flange 20 strip 151 is applied to the former 38 with its glued face outside and that the jaw 162 of the gripper is adapted to grip the web 151 between the lines of glue, and not on said lines, this jaw being provided with fingers 25 for the purpose as explained in the companion application referred to. Rotation of the cam shaft 166 is effected from the main driving shaft 13 through the instrumentality of the bevel gears 190' and 191' the vertical 30 shaft 192' and the bevel gears 193' and 194', the last being on the cam shaft 166.

The former will now be provided with the head strip 1 across its front end and a flange strip 2 coiled therearound, as illustrated diagrammatically in Fig. 35, it being understood that the head strip severed by the die 35 87 is circular and of larger diameter than that of the coil of flange strip 2 so as to provide the projecting margin 3 of the head strip. The former is then translated to station C where the circular margin 3 of the head strip is folded upon the coil of flange strip as indicated diagrammatically in Fig. 40 36. The instrumentalities for effecting this 45 folding in the present embodiment are as follows: (see Figs. 22, 23 and 24). The numeral 190 indicates an axially reciprocal rotatable cylindrical hollow head movable over the edge of the coiled flange strip 2. This 50 head thus provides a margin-folding ring and is made in two parts, and includes the margin folding ring part 191, which is the part which directly cooperates with the margin 3 of the head strip to fold the same. The 55 ring 191 is set firmly in the hollow head but may be removed therefrom for replacement and repair. Preferably the advance edge of the ring is beveled as indicated at 192. Within the ring 191 and axially reciprocal thereto 60 is a presser plate 193, and springs 194 are interposed between the plate 193 and the opposite face of the head tending to urge the presser plate toward the plane of the folding edge of the ring 191 and also toward the 65 former 38 in position at station B. The

springs may be suitably supported on pins 195 movable with the plate 193 and having heads 196 to limit outward movement of the plate relative to the ring. The margin folding ring is carried by a reciprocal support 70 or rod 197 slideable and rotatable in a bracket 198 upstanding from the table 6. The outer end of the rod 197 is so connected to a link 199 as to permit rotation of the rod in its bearing in the bracket. The link 199 is connected to a rock lever 200 fulcrumed at 201 on a bracket 202 and operated from a cam 203 through the instrumentality of a cam follower 204 and a toggle comprising links 205 and 206, a spring 207 being employed to 80 keep the follower in contact with the cam. Movable into and out of pressing relation with the coiled flange strip at station C is a forked presser 208 which straddles the central glue line 182 and presses the coiled 85 strip during the folding of the margin of the head strip. Should there be any tendency for the joint between the trailing end of the flange strip to pucker on account of the folding of the margin 3 thereon, the 90 presser 208 will, effectually counteract such tendency and keep the joint tight and smooth. The presser 208 is operated through a rock shaft 209 in a bearing 210, the shaft having an arm 211 connected to rock lever 95 212 by rod 213, the rock lever 212 being actuated to move the presser 208 away from the former by a cam 214 and cam follower 215 movement in the opposite direction being effected by the spring 216. 100

The folding ring is stationary on the support 197 and is rotatable therewith. As the ring advances toward the former at station C it meets the circular margin 3 of the head strip and simultaneously folds the full 105 circumference of this margin upon and firmly against the glued edge of the coiled flange strip 2, the bevel edge 192 easing the folding operation. In the present embodiment the timing of the movement of the folding 110 ring and the rotation of the former is such that the ring retains its folding position while the former is rotating so that the folded margin may be, as it were, ironed between the former 38 and the folding ring, 115 the fold being thereby made as smooth as possible consistent with the possible puckering of the material. The ironing may be effected by rotation of the former relative to the ring the latter being a relatively loose part. As the folding ring is retracted from folding position the springs 194 urge the plate 193 outwardly so that it presses the head strip against the end of the former, and as well serves as a keeper member to 120 prevent the paper article on the former from being displaced or withdrawn therefrom as the folder is retracted.

After the operations have been effected at station C, as explained, the former with the 130

flange and folded head strip thereon is translated to station D where a separate flange strip is applied over the folded margin of the head strip as well as over the 5 first coiled flange strip. In the present embodiment the flange strip applied at station D is of thin paper preferably finished on one side as by being glazed so as to provide a smooth surface for the outer side of 10 the flange of the "drum." The devices for applying the second flange strip are generally similar to those explained for applying the first flange strip and are illustrated in Figs. 25 to 29 inclusive. The flange strip 15 or web 220 of glazed paper coming from a supply spool indicated at 220' (Figs. 2 and 4) passes over a glue roller 221, thence over a spring tensioning device 222 which consists of a spring pressed pivoted arm having 20 an anti-friction roller 223 over which the flange strip 220 passes to the gripper jaws 224 and 225. The numeral 226 indicates a knife for cutting the flange strip 220 and the numeral 227 indicates a roller 25 for pressing the strip as it is coiled on the former 38. The gripper jaws 224 and 225 are reciprocated by a cam 228 on a cam shaft 229 through the instrumentality of the link and lever connections 230, 231 and 30 232, a spring 233 being employed to effect the advance movement of the gripper jaws, the retractive movement thereof being positively affected by the cam 228. The knife 226 is supported at the end of a slide rod 35 234 urged downwardly by a spring 235 to cooperate with a cam 236 on the cam shaft 229, the downward stroke of the knife being cushioned by a spring 237. The presser roller 227 is carried by the upper end of 40 slide rod 238 cooperating with the cam 239 on the cam shaft 229.

The presser roller 227 is urged upwardly by the spring 240 and moved downwardly by the cam 239. The cam shaft 229 is driven 45 from the main driving shaft 13 by means of a sprocket chain 241. The glue roller 221 (Figs. 1 and 4) coats with glue the full width of the flange strip 220, so that the latter, when coiled upon the previously 50 wound flange strip, adheres thereto and to the folded margin of the head strip 1. The roller 223 at all times exerts a tension on the strip 220 and rolls on the same so as to keep such strip smooth and as far as 55 possible free from curls. When applied to the former at station D the strip 220 adheres to the paper members previously formed thereon and rotation of the former serves to feed the flange strip 220, the roller 60 23 moving upwardly around the pivotal point of its supporting arm 222. When the strip 220 is severed by the knife 226 its withdrawal from between the gripper jaws by the tension effect of the roll 223 is prevented 65 by a pawl 245 (Fig. 25) pivoted to

the upper gripper jaw and having a roughened end to contact with the face of the strip 220 and arrest retraction. As the strip 220 advances under the pull of the rotating former 38 the pawl 245 yields on its pivot 70 to permit advance movement of the strip relative thereto. The gripper 225 slides in a guideway 246 on a stationary bracket 247 and so is guided to direct the flange strip 220 on to the folded margin of the head 75 strip. In order to conserve the flange strip 220, which is of relatively expensive material, and at the same time in order not to increase the thickness of the side of the drum unduly the flange strip 220 is quickly 80 severed by the knife 226, during the rotation of the former 38 so that but a single 85 ply of this material need be formed.

The former with the several strips applied thereto as previously explained then 88 makes another movement of translation, bringing the same to station E. In the present embodiment this may be regarded as an idle station where no operations are performed. The article may be inspected 90 at this station and the time taken in moving to this station and to the next station enables the glue to set somewhat.

The former then makes another movement of translation and arrives at station F 95 where the articles are discharged from the machine. By reference to Fig. 8 a discharging member 250 will be seen surrounding and overlapping the inner edge of the former 38. Each former is associated with such a 100 discharging member. In the present embodiment this member is cylindrical and its forward edge provides a shoulder 251 against which the inner edge of the two flange strips may abut as they are coiled on 105 the former, this shoulder intersecting the planes in which the coiled strips lie. The discharging member 250 is mounted on the sleeve 39 and may rotate on said sleeve. Also it is reciprocal axially relative to the 110 former, being moved inwardly by springs 252 bearing both against the formers and the discharging member, or sleeve, the springs serving to yieldingly couple the discharging member to the former for simultaneous rotation. Each of the discharging members 250 is provided with a rear conical face 253 with which cooperates a translatable coned roller 254 operable at station E to move the discharger 250 so as to discharge, or sweep, the paper articles off the end of the former whence they may fall from the machine. After discharge has been effected the spring 252 returns the discharging member to initial discharging position 115 120 and into initial cooperative position with the discharging roller 254.

The discharging roller 254 is journaled on a slide 255 mounted in a guideway on a bracket 256 upstanding from the table 6, and 130

is actuated by a bellcrank lever 257 linked at one end to the slide 255, the other end of the bellcrank being operatively connected to cooperate with the cam 258 on the cam shaft 5 20, the cam operating to positively move the discharging roller 254 in the direction to effect discharge, springs 259 and 260 cooperating to move the discharging roller in the opposite direction.

10 The operative connection between the bellcrank lever 257 and the cam 258 includes a reciprocal rod composed of sections 261 and 262. As the cam 258 operates to lower this sectional rod to thereby discharge the article 15 from the former, the article may offer such resistance to the discharging movement as to tend to fracture some of the parts of the machine or impair or mutilate the article. Accordingly under such circumstances the 20 sections 261 and 262 will become operatively detached so that, notwithstanding the operation of the cam, no substantial pressure will be exerted on the discharger 250 and, at the same time, the main clutch of the machine 25 will be shifted to throw off the power.

In order to detachably connect the two sections of the rod together a movable dog 263 is pivoted to the lower section, this dog including a taper pin, or lug 264 which engages a cooperative dog tripping surface, or recess, 265 on the upper section 261. In the specific embodiment illustrated this upper section has a squared portion 266 which enters and fits a sleeve 267 forming part of 30 the lower section. The upper section 261 is provided with oppositely projecting pins, or stops 268, which enter slots 269 in the opposite sides of the sleeve 267. The sleeve 267 is provided on one side with an opening 35 through which the taper pin 264 may enter to engage the dog tripping surface 265, which latter is a rounded surface adapted, upon movement past the pin 264, to urge such pin from the rounded recess 265 and 40 thereby operatively disconnect the sections from each other so that the descent of the lower section by operation of the cam 258 may be effected without descent of the upper section 261. Springs 270 connected to the 45 dog 263, and to the sleeve 267 urge the pin 264 into engagement with the recess 265.

Alongside the plane of movement of the dog 263 with the lower rod section 262, is a toothed plate 271 slidable in guides 272 supported by a bracket 273 underlying the table 6. The plate 271 is held in an upper position by a spring 274 connected thereto and to the bracket 273. The lower end of the plate 271 is pivoted to a link 275, in turn 50 pivoted to an arm 276 of a rock shaft 277 having another arm 278 (Fig. 33) which is adapted to contact with a lug 279 on the clutch shifter rod 280 for the main clutch of the machine. Under operation of the cam 55 258, when the taper pin 264 is in engagement

with the recess 265, the two rod sections 261 and 262 move as one and impart proper motion to the coned roller 254 for reciprocating the latter to effect operation of the discharger 250. Should resistance to the movement of the sectional connecting rod occur, the pin 264 will be forced out of the recess 265 in the section 261 and permit movement of the lower section by the cam without consequent movement of the upper section, 75 which latter may remain idle at that time. When the dog 263 is forced outwardly in this manner a tooth 281 carried thereby will engage one or the other of the teeth in the plate 271 and, on downward movement of 80 the lower section 262, will move the plate 271 downwardly so as to rock the shaft 277 and cause the arm 278 to strike the lug 279 and thereby throw out the main clutch of the machine.

85 The operation of the machine will be clear from the foregoing and need not be further described. It may be noted, however, that by the construction herein disclosed is provided a fully automatic machine, and by means of which both the flanges and the heads of paper boxes or "drums" may be made and assembled in their operative relationship. In its specific embodiment disclosed herein the invention 90 is exemplified by a fully automatic machine which makes cylindrical "drums," the head of the "drum" being composed of soft frangible paper which may be readily punctured, or broken, as by pressing the fingers of the 95 hand thereagainst. One of the utilities of the "drum" referred to is as an accessory to a face powder box, the open end of the drum being inserted in the box so that the drum overlies the powder therein and the head of the drum is exposed when the cover of the 100 box is removed. To obtain ready access to the powder in the box the head of the drum may be punctured as explained. In Fig. 41, one of the drums made by the 105 machine is illustrated and Fig. 42 illustrates, partly in section, a face powder box provided with such a drum. In operating the machine it is merely required that the machine be equipped with glue as explained 110 and that suitable head strips and flange strips be supplied, whereupon, by actuation of the machine, the different elements will coordinate to cause the flange strips from one of the supply devices to be coiled on the 115 sides of the formers, head strips from another of the supply devices to be applied across the ends of the formers and their margins folded on to the coiled strips, and flange strips from another of the supply 120 devices to be coiled by the formers over the previously coiled flange strips. Inasmuch as the operations of coiling and applying the strips to the several formers will be effected simultaneously the machine is of 125 130

large capacity and is capable of turning out a great number of drums within a relatively short time.

Thus by the above described construction 5 are accomplished among others the objects hereinabove referred to.

The invention accordingly consists in the features of construction, combinations of elements and arrangement of parts which 10 will be exemplified in the construction hereinafter set forth, and the scope of the application of which will be indicated in the following claims.

As many changes could be made in the 15 above construction and many apparently widely different embodiments of this invention could be made without departing from the scope thereof, it is intended that all matter contained in the above description 20 or shown in the accompanying drawings shall be interpreted as illustrative and not in a limiting sense.

Having described my invention, what I claim as new and desire to secure by Letters 25 Patent is:—

1. In a machine of the character described, in combination, a plurality of formers, means adapted to translate said formers in an endless path intermittently, 30 means adapted to rotate said formers at their stations of rest in said endless path to coil strips thereon, strip supply devices, a strip folding device, and means adapted to coordinate the operations of the before-mentioned 35 elements to cause flange strips from one of said supply devices to be coiled on the sides of said formers, head strips from another of said supply devices to be applied across ends of said formers and their margins 40 folded onto the coiled strips and flange strips from another of said supply devices to be coiled over the previously coiled strips.

2. In a machine of the character described, in combination, a plurality of formers, 45 means adapted to translate said formers in an endless path intermittently, means adapted to rotate said formers at their stations of rest in said endless path to coil strips thereon, strip supply devices, a strip 50 folding device, and means adapted to coordinate the operations of the before-mentioned elements to cause flange strips from one of said supply devices to be coiled on the sides of said formers, head strips from another of said supply devices to be applied across ends of said formers and their margins 55 folded onto the coiled strips and flange strips from another of said supply devices to be coiled over the previously coiled strips, 60 and to cause said coiling simultaneously with said folding.

3. In a machine of the character described, in combination, a plurality of formers, 65 means adapted to translate said formers in an endless path intermittently, means adapt-

ed to rotate said formers at their stations of rest in said endless path to coil strips thereon, strip supply devices, a strip folding device, and means adapted to coordinate the operations of the before-mentioned elements to cause flange strips from one of said supply devices to be coiled on the sides of said formers, head strips from another of said supply devices to be applied across ends of said formers and their margins folded 70 onto the coiled strips and flange strips from another of said supply devices to be coiled over the previously coiled strips, the device for supplying head strips including a reciprocal cutting die adapted to sever such strips 75 from within the margins of a web.

4. In a machine of the character described, in combination, a plurality of formers, means adapted to translate said formers in an endless path intermittently, means adapted to rotate said formers at their stations of rest in said endless path to coil strips thereon, strip supply devices, a strip folding device, and means adapted to co-ordinate the operations of the before-mentioned elements to cause flange strips from one of said supply devices to be coiled on the sides of said formers, head strips from another of said supply devices to be applied across ends of said formers and their margins 90 folded onto the coiled strips and flange strips from another of said supply devices to be coiled over the previously coiled strips, the device for supplying head strips including a reciprocal cutting die adapted to sever such strips 95 from within the margins of a web and movable to apply the severed strips to the formers.

5. In a machine of the character described, in combination, a plurality of formers, 105 means adapted to translate said formers in an endless path intermittently, means adapted to rotate said formers at their stations of rest in said endless path to coil strips thereon, strip supply devices, a strip folding device, means adapted to co-ordinate the operations of the before-mentioned elements to cause flange strips from one of said supply devices to be coiled on the sides of said formers, head strips from another 110 of said supply devices to be applied across ends of said formers and their margins folded onto the coiled strips and flange strips from another of said supply devices to be coiled over the previously coiled strips, the 115 devices for supplying head strips, including a reciprocal cutting die adapted to sever such strips from within the margins of a web and movable to apply the severed strips to the formers, the advance end of said die 120 having vacuum ports for gripping the severed strips, and means adapted to energize and de-energize said ports at predetermined times.

6. In a machine of the character described, 130

in combination, a plurality of formers, means adapted to translate said formers in an endless path intermittently, means adapted to rotate said formers at their stations of rest in said endless path to coil strips thereon, strip supply devices, a strip folding device, means adapted to co-ordinate the operations of the before-mentioned elements to cause flange strips from one of said supply devices to be coiled on the sides of said formers, head strips from another of said supply devices to be applied across ends of said formers and their margins folded onto the coiled strips and flange strips from another of said supply devices to be coiled over the previously coiled strips, the device for supplying head strips including a reciprocal cutting die adapted to sever such strips from within the margins of a web and movable to apply the severed strips to the formers, the advance end of said die having vacuum ports for gripping the severed strips, means adapted to energize and de-energize the vacuum ports in said die and said formers at predetermined intervals, and means for controlling the energization and de-energization of the vacuum ports in said die separately from those of said formers.

15 from another of said supply devices to be coiled over the previously coiled strips, the device for supplying head strips including a reciprocal cutting die adapted to sever such strips from within the margins of a web and movable to apply the severed strips to the formers, the advance end of said die having vacuum ports for gripping the severed strips, means adapted to energize and de-energize said ports at predetermined 20 times including a vacuum conduit leading from said ports, a rock-plate having a port in communication with said conduit, and a cut-off plate lying closely against said rock-plate having a port with which the 25 port in said rock-plate is adapted to register.

30

7. In a machine of the character described, in combination, a plurality of formers, means adapted to translate said formers in an endless path intermittently, means adapted to rotate said formers at their stations of rest in said endless path to coil strips thereon, strip supply devices, a strip folding device, means 35 adapted to co-ordinate the operations of the before-mentioned elements to cause flange strips from one of said supply devices to be coiled on the sides of said formers, head strips from another of said supply devices to be applied across ends of said formers and their margins folded onto the coiled strips and flange strips from another of said supply devices to be coiled over the previously coiled strips, the device for supplying head strips including a reciprocal cutting die adapted to sever such strips from within the margins of a web and movable to apply the severed strips to the formers, the advance end of said die having vacuum ports for gripping the severed strips, means adapted to energize and de-energize said ports at predetermined times, intermittently operated friction rollers for advancing the web past the cutting die, and a spring tension device operative on the web in advance of said friction rollers.

on, strip supply devices, a strip folding device, means adapted to co-ordinate the operations of the before-mentioned elements to cause flange strips from one of said supply devices to be coiled on the sides of said formers, head strips from another of said supply devices to be applied across ends of said formers and their margins folded onto the coiled strips and flange strips from another of said supply devices to be coiled over the previously coiled strips, the device for supplying head strips including a reciprocal cutting die adapted to sever such strips from within the margins of a web and movable to apply the severed strips to the formers, the advance end of said die and the ends of said formers having vacuum ports for gripping the severed strip, means adapted to energize and de-energize the vacuum ports in said die and said formers at predetermined intervals, and means for controlling the energization and de-energization of the vacuum ports in said die separately from those of said formers.

9. In a machine of the character described, in combination, a plurality of formers, means adapted to translate said formers in an endless path intermittently, means adapted to rotate said formers at their stations of rest in said endless path to coil strips thereon, strip supply devices, a strip folding device, means adapted to co-ordinate the operations of the before-mentioned elements to cause flange strips from one of said supply devices to be coiled on the sides of said formers, head strips from another of said supply devices to be applied across ends of said formers and their margins folded onto the coiled strips and flange strips from another of said supply devices to be coiled over the previously coiled strips, the device for supplying head strips including a reciprocal cutting die adapted to sever such strips from within the margins of a web and movable to apply the severed strips to the formers, the advance end of said die having vacuum ports for gripping the severed strips, means adapted to energize and de-energize said ports at predetermined times, intermittently operated friction rollers for advancing the web past the cutting die, and a spring tension device operative on the web in advance of said friction rollers.

10. In a machine of the character described, in combination, a plurality of formers, means adapted to translate said formers in an endless path intermittently, means adapted to rotate said formers at their stations of rest in said endless path to coil strips thereon, strip supply devices, a strip folding device, means adapted to co-ordinate the operations of the before-mentioned elements to cause flange strips from one of said supply devices to be coiled on the sides of said formers, head strips from another of said supply devices to be applied across ends of said formers and their margins folded onto the coiled strips and flange strips from another of said supply devices to be coiled over the previously coiled strips, the device for supplying head strips including a reciprocal cutting die adapted to sever such strips from within the margins of a web and movable to apply the severed strips to the formers, the advance end of said die having vacuum ports for gripping the severed strips, means adapted to energize and de-energize said ports at predetermined times, intermittently operated friction rollers for advancing the web past the cutting die, and a spring tension device operative on the web in advance of said friction rollers.

- formers in an endless path intermittently, means adapted to rotate said formers at their stations of rest in said endless path to coil strips thereon, strip supply devices, a strip folding device, means adapted to co-ordinate the operations of the before-mentioned elements to cause flange strips from one of said supply devices to be coiled on the sides of said formers, head strips from another of said supply devices to be applied across ends of said formers and their margins folded onto the coiled strips and flange strips from another of said supply devices to be coiled over the previously coiled strips, 10 said translating means including a plurality of annularly grooved arms concentric with said formers and on which the formers are rotatively mounted, respectively, the front ends and the sides of said formers including vacuum ports for gripping the head strips and the first mentioned flange strips, vacuum conduits leading from the side ports to the annular grooves, annular vacuum conduits, vacuum conduits connecting said annular conduits with the ports in the ends of said formers, and independent vacuum conduits in said arms in communication, respectively, with said annular grooves and annular conduits, an exhaust-device, and 20 means adapted to establish and cut off communication between said exhaust device and the vacuum conduits in said arms at predetermined times.
16. In a machine of the character described, in combination, a plurality of formers, means adapted to translate said formers in an endless path intermittently, means adapted to rotate said formers at their stations of rest in said endless path to coil strips thereon, strip supply devices, a strip folding device, means adapted to co-ordinate the operations of the before-mentioned elements to cause flange strips from one of said supply devices to be coiled on the sides of said formers, head strips from another of said supply devices to be applied across ends of said formers and their margins folded onto the coiled strips and flange strips from another of said supply devices to be coiled over the previously coiled strips, the device for supplying head strips including a reciprocal cutting die adapted to sever such strips from a web of head strip material and movable to apply the severed strips to the formers, the advance end of said die and the ends and sides of said formers having vacuum ports for gripping the strips supplied thereto, and devices for controlling energization of the die ports independently of that of said ports in the former.
17. In a machine of the character described, in combination, a plurality of formers, means adapted to translate said formers in an endless path intermittently, means adapted to rotate said formers at their stations of rest in said endless path to coil strips thereon, strip supply devices, a strip folding device, means adapted to co-ordinate the operations of the before-mentioned elements to cause flange strips from one of said supply devices to be coiled on the sides of said formers, head strips from another of said supply devices to be applied across ends of said formers and their margins folded onto the coiled strips and flange strips from another of said supply devices to be coiled over the previously coiled strips, said strip folding device including an axially reciprocal rotatable margin-folding 125
18. In a machine of the character described, in combination, a plurality of formers, means adapted to translate said formers in an endless path intermittently, means adapted to rotate said formers at their stations of rest in said endless path to coil strips thereon, strip supply devices, a strip folding device, means adapted to co-ordinate the operations of the before-mentioned elements to cause flange strips from one of said supply devices to be coiled on the sides of said formers, head strips from another of said supply devices to be applied across ends of said formers and their margins folded onto the coiled strips and flange strips from another of said supply devices to be coiled over the previously coiled strips, the device for supplying head strips including a reciprocal cutting die adapted to sever such strips from a web of head strip material and movable to apply the severed strips to the formers, the advance end of said die and the ends and sides of said formers having vacuum ports for gripping the strips supplied thereto.
19. In a machine of the character described, in combination, a plurality of formers, means adapted to translate said formers in an endless path intermittently, means adapted to rotate said formers at their stations of rest in said endless path to coil strips thereon, strip supply devices, a strip folding device, means adapted to co-ordinate the operations of the before-mentioned elements to cause flange strips from one of said supply devices to be coiled on the sides of said formers, head strips from another of said supply devices to be applied across ends of said formers and their margins folded onto the coiled strips and flange strips from another of said supply devices to be coiled over the previously coiled strips, said strip folding device including an axially reciprocal rotatable margin-folding 130

ring, at one of said stations, movable over the edge of the coiled first mentioned flange strip, and a head-strip presser plate axially reciprocal within said ring. 20. In a machine of the character described, in combination, a plurality of formers, means adapted to translate said formers in an endless path intermittently, means adapted to rotate said formers at their stations of rest in said endless path to coil strips thereon, strip supply devices, a strip folding device, means adapted to coordinate the operations of the before-mentioned elements to cause flange strips from one of said supply devices to be coiled on the sides of said formers, head strips from another of said supply devices to be applied

sides of said formers, head strips from another of said supply devices to be applied across ends of said formers and their margins folded onto the coiled strips and flange strips from another of said supply devices to be coiled over the previously coiled strips, said strip folding device including an axially reciprocal rotatable margin-folding ring with beveled advance edge, at one of said stations, movable over the edge of the coiled first mentioned flange strip and a head-strip presser plate axially reciprocal within said ring, and spring means to urge said presser plate toward said former on movement of said ring from overlapping relation with said coiled strip. 70 75 80 85

other of said supply devices to be applied across ends of said formers and their margins folded onto the coiled strips and flange strips from another of said supply devices to be coiled over the previously coiled strips, said strip folding device including an axially reciprocal rotatable margin-folding ring, at one of said stations, movable over the edge of the coiled first mentioned flange strip, a head strip presser plate axially reciprocal within said ring, and spring means to urge said presser plate toward said former on movement of said ring from overlapping relation with said coiled strip.

23. In a machine of the character described, in combination, a plurality of formers, means adapted to translate said formers in an endless path intermittently, means adapted to rotate said formers at their stations of rest in said endless path to coil strips thereon, strip supply devices, a strip folding device, means adapted to co-ordinate the operations of the before-mentioned elements to cause flange strips from one of said supply devices to be coiled on the sides of said formers, head strips from another of said supply devices to be applied across ends of said formers and their margins folded onto the coiled strips and flange strips from another of said supply devices to be coiled over the previously coiled strips, said strip folding device including an axially reciprocal rotatable margin-folding ring, at one of said stations, movable over the edge of the coiled first mentioned flange strip, a head strip presser plate axially reciprocal within said ring, and spring means to urge said presser plate toward said former on movement of said ring from overlapping relation with said coiled strip.

21. In a machine of the character described, in combination, a plurality of formers, means adapted to translate said formers in an endless path intermittently, means adapted to rotate said formers at their stations of rest in said endless path to coil strips thereon, strip supply devices, a strip folding device, means adapted to co-ordinate the operations of the before-mentioned elements to cause flange strips from one of said supply devices to be coiled on the sides of said formers, head strips from another of said supply devices to be applied across ends of said formers and their margins folded onto the coiled strips and flange strips from another of said supply devices to be coiled over the previously coiled strips, said strip folding device including an axially reciprocal rotatable margin-folding ring, at one of said stations, movable over the edge of the coiled first-mentioned flange-strip, a device adapted to glue the outer face of the first mentioned flange strip on lines spaced apart transversely of such strip, and a forked presser adapted to straddle one of said glue lines and press against the strip during coiling thereof and folding of the margin of said head strip.

24. In a machine of the character described, in combination, a plurality of formers, means adapted to translate said formers in an endless path intermittently, means adapted to rotate said formers at their stations of rest in said endless path to coil strips thereon, strip supply devices, a strip folding device, means adapted to co-ordinate the operations of the before-mentioned elements to cause flange strips from another of said supply devices to be coiled on the sides of said formers, head strips from another of said supply devices to be applied across ends of said formers and their margins folded onto the coiled strips and flange strips from another of said supply devices to be coiled over the previously coiled strips, said strip folding device including an axially reciprocal rotatable margin-folding ring, at one of said stations, movable over the edge of the coiled first-mentioned flange-strip, a device adapted to glue the outer face of the first mentioned flange strip on lines spaced apart transversely of such strip, and a forked presser adapted to straddle one of said glue lines and press against the strip during coiling thereof and folding of the margin of said head strip.

55 22. In a machine of the character described, in combination, a plurality of formers, means adapted to translate said formers in an endless path intermittently, means adapted to rotate said formers at 60 their stations of rest in said endless path to coil strips thereon, strip supply devices, a strip folding device, means adapted to coordinate the operations of the before-mentioned elements to cause flange strips from 65 one of said supply devices to be coiled on the to cause flange strips from one of said supply devices to be coiled on the sides of said formers, head strips from another of said supply devices to be applied across ends of said formers and their margins folded onto the coiled strips and flange strips from another of said supply devices to be coiled over 125 the previously coiled strips, said strip folding device including an axially reciprocal rotatable margin-folding ring, at one of said stations, movable over the edge of the coiled first mentioned flange strip, a device adapted 130

to glue the outer face of the first mentioned flange strip on lines spaced apart transversely of such strip, a forked presser adapted to straddle one of said glue lines and 5 press against the strip during coiling thereof and folding of the margin of said head strip, said strip supply devices including a guide for directing said second mentioned flange strip onto the folded margin of the head 10 strip and devices for coating the inner face of said second mentioned flange strip with glue to secure adherence to said folded margin.

25. In a machine of the character described, in combination, a plurality of formers, means adapted to translate said formers in an endless path intermittently, means adapted to rotate said formers at their stations of rest in said endless path to coil strips 20 thereon, strip supply devices, a strip folding device, means adapted to co-ordinate the operations of the before-mentioned elements to cause flange strips from one of said supply devices to be coiled on the sides of 25 said formers, head strips from another of said supply devices to be applied across ends of said formers and their margins folded onto the coiled strips and flange strips from another of said supply devices to be coiled 30 over the previously coiled strips, rotatable members providing shoulders on the sides of said formers, respectively, intersecting the planes of the coiled strip, and means adapted to move said members axially relative to 35 said formers at one of said stations to discharge the coiled strips from said formers.

26. In a machine of the character described, in combination, a plurality of formers means adapted to translate said formers 40 in an endless path intermittently, means adapted to rotate said formers at their stations of rest in said endless path to coil strips thereon, strip supply devices, a strip folding device, means adapted to co-ordinate the 45 operations of the before-mentioned elements to cause flange strips from one of said supply devices to be coiled on the sides of said formers, head strips from another of said supply devices to be applied across ends of 50 said formers and their margins folded onto the coiled strips and flange strips from another of said supply devices to be coiled over the previously coiled strips, rotatable members providing shoulders on the sides of said 55 formers, respectively, intersecting the planes of the coiled strip, means adapted to move said members axially relative to said formers at one of said stations to discharge the coiled strips from said formers, including conical 60 faces on said members and a translatable coned roller adapted to engage said faces.

27. In a machine of the character described, in combination, a plurality of formers, means adapted to translate said formers 65 in an endless path intermittently, means

adapted to rotate said formers at their stations of rest in said endless path to coil strips thereon, strip supply devices, a strip folding device, means adapted to co-ordinate the operations of the before-mentioned elements to cause flange strips from one of said supply devices to be coiled on the sides of said formers, head strips from another of said supply devices to be applied across ends of said formers and their margins folded 70 onto the coiled strips and flange strips from another of said supply devices to be coiled over the previously coiled strips, and discharging members translatable with said formers, respectively, rotatable relative 75 thereto, and reciprocal axially thereof.

28. In a machine of the character described, in combination, a plurality of formers, means adapted to translate said formers in an endless path intermittently, means 80 adapted to rotate said formers at their stations of rest in said endless path to coil strips thereon, strip supply devices, a strip folding device, means adapted to co-ordinate the operations of the before-mentioned elements to cause flange strips from one of said supply devices to be coiled on the sides of said formers, head strips from another of said supply devices to be applied across 85 ends of said formers and their margins folded onto the coiled strips and flange strips from another of said supply devices to be coiled over the previously coiled strips, discharging members translatable with said formers, respectively, rotatable relative 90 thereto and reciprocal axially thereof, and springs adapted to yieldingly couple said members and formers for simultaneous rotation.

29. In a machine of the character described, in combination, a plurality of formers, means adapted to translate said formers in an endless path intermittently, means adapted to rotate said formers at their stations of rest in said endless path to coil strips thereon, strip supply devices, a strip folding device, means adapted to co-ordinate the operations of the before-mentioned elements to cause flange strips from one of said supply devices to be coiled on the sides of said formers, head strips from another of said supply devices to be applied across ends of said formers and their margins folded onto the coiled strips and flange strips from another of said supply devices to be coiled over the previously coiled strips, discharging members translatable with said formers, respectively rotatable relative thereto, and reciprocal axially thereof, and springs adapted to yieldingly couple said members and formers for simultaneous rotation, said springs operatively associated to effect axial movement of said discharging members in one direction.

30. In a machine of the character de- 130

- scribed, in combination, a plurality of formers, means adapted to translate said formers in an endless path intermittently, means adapted to rotate said formers at their stations of rest in said endless path to coil strips thereon, strip supply devices, a strip folding device, means adapted to co-ordinate the operations of the before-mentioned elements to cause flange strips from one of said supply devices to be coiled on the sides of said formers, head strips from another of said supply devices to be applied across ends of said formers and their margins folded onto the coiled strips and flange strips from another of said supply devices to be coiled over the previously coiled strips, discharging sleeves coaxial with said formers, respectively, translatable therewith and rotatable and reciprocal relative thereto, and springs bearing both against said formers and said sleeves and adapted to rotate therewith.
31. In a machine of the character described, in combination, a plurality of formers, means adapted to translate said formers in an endless path intermittently, means adapted to rotate said formers at their stations of rest in said endless path to coil strips thereon, strip supply devices, a strip folding device, means adapted to co-ordinate the operations of the before-mentioned elements to cause flange strips from one of said supply devices to be coiled on the sides of said formers, head strips from another of said supply devices to be applied across ends of said formers and their margins folded onto the coiled strips and flange strips from another of said supply devices to be coiled over the previously coiled strips, a reciprocal member at one of said stations adapted to contact with and discharge from said formers the articles formed thereon, means adapted to reciprocate said member including a member-operating reciprocal sectional rod, and means for detachably connecting said sections together including a movable dog on one section and a co-operative dog tripping surface on the other section.
32. In a machine of the character described, in combination, a plurality of formers, means adapted to translate said formers in an endless path intermittently, means adapted to rotate said formers at their stations of rest in said endless path to coil strips thereon, strip supply devices, a strip folding device, means adapted to co-ordinate the operations of the before-mentioned elements to cause flange strips from one of said supply devices to be coiled on the sides of said formers, head strips from another of said supply devices to be applied across ends of said formers and their margins folded onto the coiled strips and flange strips from another of said supply devices to be coiled over the previously coiled strips, a recipro-
- cal member at one of said stations adapted to contact with and discharge from said formers the articles formed thereon, means adapted to reciprocate said member including a member-operating reciprocal sectional rod, means for detachably connecting said sections together including a movable dog on one section and a co-operative dog tripping surface on the other section, and a clutch-shifter operating device adapted to be engaged by said dog on detachment of said sections.
33. In a machine of the character described, in combination, a bearing having a circumferential groove, a former rotatable on said bearing having a vacuum port in its side in communication with said groove, a vacuum conduit in said bearing in communication with said groove, a second vacuum conduit in said bearing leading to a port in the end of the bearing, a vacuum port in the end of said former, and means adapted to maintain communication between said second vacuum conduit and the end port in said former as the former rotates.
34. In a machine of the character described, in combination, a bearing having a circumferential groove, a former rotatable on said bearing having a vacuum port in its side in communication with said groove, a vacuum conduit in said bearing in communication with said groove, a second vacuum conduit in said bearing leading to a port in the end of the bearing, a vacuum port in the end of said former, and means adapted to maintain communication between said second vacuum conduit and the end port in said former as the former rotates, including an endless vacuum conduit in registry with the end port in said bearing.
35. In a machine of the character described, in combination, a bearing having a circumferential groove, a former rotatable on said bearing having a vacuum port in its side in communication with said groove, a vacuum conduit in said bearing in communication with said groove, a second vacuum conduit in said bearing leading to a port in the end of the bearing, a keeper plate removably fastened to the end of said bearing having a port in registry with the port in the end of said bearing, a vacuum plate removably fastened to the end of said former having on its inner face a circular groove in registry with the port in said keeper plate and having one or more vacuum ports in communication with said circular groove.
36. In a machine of the character described, in combination, a bearing having a circumferential groove, a former rotatable on said bearing having a vacuum port in its side in communication with said groove, a vacuum conduit in said bearing in communication with said groove, a second vac-

uum conduit in said bearing leading to a port in the end of the bearing, a vacuum port in the end of said former, means adapted to maintain communication between said second vacuum conduit and the end port in said former as the former rotates, an exhaust device, and an automatically operable valve adapted to establish communication between said exhaust device and said vacuum conduits in said bearing.

37. In a machine of the character described, in combination, a bearing having a circumferential groove, a former rotatable on said bearing having a vacuum port in its side in communication with said groove, a vacuum conduit in said bearing in communication with said groove, a second vacuum conduit in said bearing leading to a port in the end of the bearing, a vacuum port in the end of said former, means adapted to maintain communication between said second vacuum conduit and the end port in said former as the former rotates, an exhaust device, and an automatically operable valve adapted to establish communication between said exhaust device and said vacuum conduits in said bearing, said valve having vacuum relief ports adapted to register with said last mentioned conduits at predetermined times.

38. In a machine of the character described, in combination, a reciprocal circular male cutting die, a co-operative female cutting die, means adapted to feed a strip between said dies to be cut thereby, the advance face of said male die having one or more vacuum ports adapted to grip the severed section of said strip.

39. In a machine of the character described, in combination, a reciprocal circular male cutting die, a co-operative female cutting die, a former adapted to assume position opposite said female die, means adapted to reciprocate said male die and effect cutting of said strip including a link, one

end of which is pivotally connected to said male die, a toggle one member of which is operatively connected to said link, a movable fulcrum to which said link is positively connected, and means adapted to hold said fulcrum stationary while said strip is cut. 50

40. In a machine of the character described, in combination, a reciprocal circular male cutting die, a co-operative female cutting die, a former adapted to assume position opposite said female die, means adapted to reciprocate said male die and effect cutting of said strip including a link, one end of which is pivotally connected to said male die, a toggle, one member of which is operatively connected to said link, a movable fulcrum to which said link is positively connected, means adapted to hold said fulcrum stationary while said strip is cut, and means to reciprocate said fulcrum and thereby advance said male die to and withdraw it from said former. 60

41. In a machine of the character described, in combination, a reciprocal support, a folding ring stationarily mounted on said support, a strip presser plate movable axially in said ring and springs within said ring co-operating to urge said plate toward the plane of the folding edge of said ring. 70

42. In a machine of the character described, in combination, a reciprocal support including a hollow head, a folding ring set in said head, a presser plate in said ring and movable axially thereof, and springs in said ring abutting said plate and head adapted to urge said plate outwardly of said head. 80

In testimony whereof I affix my signature, in the presence of two witnesses.

HAROLD CARLE.
